UNITED STATES PATENT OFFICE.

FREDERICK R. LAWRENCE, OF BROOKLYN, NEW YORK.

TILE.

SPECIFICATION forming part of Letters Patent No. 707,125, dated August 19, 1902.

Application filed February 4, 1902. Serial No. 92,542. (No model.)

To all whom it may concern:

Be it known that I, FREDERICK R. LAWRENCE, a citizen of the United States, and a resident of Brooklyn, New York city, in the county of Kings and State of New York, have invented certain new and useful Improvements in Tiles, of which the following is a specification.

My invention relates to tiles for ceilings, 10 floorings, and similar purposes, and has for its object to provide a tile which may be firmly joined to the cement or other foundation in which it is embedded and to the adjoining tiles.

15 The invention consists in the novel construction of a tile and the providing of certain recesses or sockets therein, as hereininafter more particularly described.

In the accompanying drawings, Figure 1 20 represents a plan view of the bottom or under side of a tile constructed according to my invention. Fig. 2 is a transverse vertical section, Fig. 3 a side view, and Fig. 4 a plan view, of the under side of three tiles, illustrating the correlation of the recesses when 25 said tiles are laid in courses or series.

In carrying my invention into effect I provide a tile *a* of the usual or any suitable material, shape, and size, and I form on the under side thereof, around the margin or edge, a 30 series of recesses or sockets *b b*. These recesses are in plan view wider at their inner ends than at their outer ends, their side walls inclining toward each other, as shown in Figs. 35 1 and 4. The bottoms or floors *c* of the recesses *b* are not flat, (see Fig. 2,) but incline so that the recesses are deeper at their outer ends than at their inner ends; but I prefer not to make them extend until the floors meet 40 the side of the tile, but rather to terminate said floors at a low vertical rear wall *c*. All the walls are preferably substantially smooth and perpendicular, or nearly so, to the side of the tile, there being no undercuts or 45 grooves, though there may be, if desired, a slight outward flare or inclination of the walls from the floor of the recess to the top of the said walls.

In using tiles constructed according to my 50 invention they are laid upon a bed of cement or similar material with the recessed side down and pressed firmly into said cement, which thereupon fills the recesses *b* and upon hardening holds the tile much more securely 55 against both vertical and lateral movement.

than if the lower side of the tile were smooth. The object and advantage of having the recesses of the shape described will be evident from Fig. 4, which shows that when tiles are laid in contiguous courses or series the recesses 60 of adjacent tiles may easily be arranged so as to correspond and form a joint recess of such shape that when the cement into which the tiles are pressed rises up into the same and hardens it forms a double wedge, which securely dovetails the adjacent tiles together. The object of making the floor of the recess inclined, so that the recess is deeper at its outer end, is to prevent the imprisonment of air in the recess when the tile is forced into 70 the cement. The object of making the walls substantially smooth and perpendicular, or nearly so, to the surface of the tile—that is, not provided with either grooves or undercuts—is because a tile of this construction 75 can be stamped or pressed out by a suitable die at one operation, which would not be the case if grooves or undercuts were a part of the construction; but a slight outward flare of the walls is advantageous, because it facilitates the lifting or drawing out of the die after the tile has been stamped. Undercuts or grooves, though difficult to form, are still possible and are advantageous, because they afford a better means of attachment to the 85 cement, and I do not limit myself to tiles either with or without undercuts or grooves, though, as stated above, smooth and vertical or nearly vertical walls are the most practicable.

Having thus described my invention, what I claim as new, and desire to secure by Letters Patent, is as follows:

A tile provided with recesses in its under surface and around the margins thereof, the 95 floors or bottoms of said recesses being inclined or sloping so that the recesses are deeper at their outer ends than at their inner ends, and the side walls of said recesses being inclined together so that the recesses are 100 wider at their inner ends than at their outer ends.

Signed at Manhattan, New York city, in the county of New York and State of New York, this 29th day of January, A. D. 1902. 105

FREDERICK R. LAWRENCE.
